John B. Gourlay

Inventor;

G. C. Gourlay

UNITED STATES PATENT OFFICE.

GEORGE C. GOURLAY, OF NEW YORK, N. Y., ASSIGNOR TO HIMSELF AND ANDREW HUNTLEY, OF SAME PLACE.

POR-T-LIGHT FOR VESSELS.

Specification of Letters Patent No. 30,519, dated October 23, 1860.

To all whom it may concern:

Be it known that I, GEORGE C. GOURLAY, of the city, county, and State of New York, have invented a new and useful Improvement 5 in Port-Lights for Vessels of Navigation; and I do hereby declare that the following is a full, clear, and exact description of the same, reference being had to the annexed drawings, making a part of this specification, in which—

Figure 1 is a detached front or face view of my invention. Fig. 2 a view of the outer side of the same detached from the vessel. Fig. 3 a horizontal section of the 15 same attached to a vessel. *x, x*, Fig. 1, indicate the plane of section.

Similar letters of reference indicate corresponding parts in the several figures.

The object of the invention is to obtain 20 a port-light that may be applied to vessels, either iron or wooden ones, with facility and so as to form a perfectly water-tight joint.

To enable those skilled in the art to fully understand and construct my invention, I 25 will proceed to describe it.

A, represents an annular rim or case which may be of brass or cast-iron and *B*, is an annular frame of the same material and which is connected to the rim or case *A*, 30 by joints *a, a*.

The inner side of the rim or case *A*, has an annular groove or recess *b*, formed in it, which groove or recess causes an annular edge *c*, at the inner edge of the rim or case 35 *A*, against which an annular rubber packing *d*, in the frame *B*, is pressed when the frame *B*, is closed—see Fig. 3.

The frame *B* is provided with the usual glass *C*, and is secured firmly in a properly 40 closed state against the rim or case *A* by buttons *D, D*, which are secured to the rim or case *A* and project over on the frame *B* when the latter is closed—see Fig. 1.

The outer side of the rim or case *A* has 45 an annular groove or recess *e*, in it. This groove or recess *e*, is about in line with the outer edge of the groove or recess *b*, as

shown clearly in Fig. 3. The rim or case *A* extends out from the groove *b*, sufficiently to admit of screw holes *f*, being made 50 through it.

The groove or recess *e*, is filled with a suitable cement *e'*, white and red lead mixed in about equal proportion will answer a good purpose.

The outer side of the rim or case *A* is fitted or placed against the inner side of the vessel *g*, and secured thereto by screws *h*, the side of the vessel around the port hole being in contact with a flanch *i*, of the rim or case 60 as shown clearly in Fig. 3.

In screwing up the screws *h*, the rim or case *A* is fitted or brought snugly up against the side of the vessel the recesses or grooves *b, e*, admitting of a requisite degree of yielding of the case transversely so as to form a perfect joint, the packing or cement *e'*, performing its usual function, and being brought up snugly in contact with the sides 65 of the vessel.

More than one annular cement groove *e* may be employed if deemed necessary. The grooves serve to retain the cement, preventing it from separating or becoming misplaced. Where a packing such as rubber or 75 other soft material is introduced, between the face of the frame *A* and the siding of the vessel, the frame *A* when screwed up is liable to spring or warp and injure the frame and become leaky.

I do not claim the employment or use of the rubber packing *d*, applied to the frame *B*, for that has been previously used; but

Having thus described my invention what I do claim as new and desire to secure by 85 Letters Patent is—

The construction of the face of the rim *A* with one or more annular grooves *e*, as herein shown and described.

GEORGE C. GOURLAY.
